UNITED STATES PATENT OFFICE.

ABRAHAM L. LEVY, OF PORTLAND, OREGON.

LOCK.

Application filed August 31, 1925. Serial No. 53,533.

My invention relates to control mechanism for drums and other lifting or moving devices and especially to locking mechanism therefor, said control devices being arranged to permit the operating mechanism to be moved freely into one position and said locking devices being adapted to hold said mechanism in said position to prevent its return movement.

10 In this respect my present application is intended to be used in connection with my invention covering railroad toilet described in my co-pending application for patent, which was filed August 31, 1925 and has developed into Patent No. 1,604,456, October 26, 1926.

15 The object of my invention is to provide mechanism of this character in which the operating and the controlling portions are provided with identically arranged key-receiving elements, so that a single key can engage either of said elements. This is particularly advantageous in locking the controls for railway toilets by the car attendant who 20 may thus engage or release said controls and may do so with a single key, such for example, as the one used by a Pullman porter to lock up the bedding in the berths.

25 A further object of my invention is to provide operating mechanism of this character which is arranged to be moved to fully extended position in one direction and locked, said locking mechanism being releasable without requiring relative movement of 30 said operating mechanism. That is, the object of my invention is to provide operating mechanism which permits the devices controlled, to be seated tightly in place in one direction and to be held tightly in position. 35 The releasing mechanism is adapted to operate without requiring said parts to become unseated. The latter object is attained by 40 providing a cam-operated pawl upon the ratchet control for the operating mechanism, said pawl being arranged so that the 45 face of the tooth thereof is substantially tangential to its pivotal point, thus the cam is permitted to lift said pawl and thus to unseat said tooth without requiring the operating mechanism to be slackened off.

50 The details of construction and mode of operation are hereinafter described with reference to the accompanying drawings, in which:

55 Fig. 1 is a diagrammatic elevation of my improved mechanism shown as connected to

draw in and pay out the cable by which toilet closure mechanism is actuated, said parts being shown somewhat out of proportion to disclose details of said control mechanism; 60

Fig. 2 is a transverse section through the drum and the locking mechanism therefor, taken substantially on the line 2-2 of Fig. 3;

Fig. 3 is a section taken on the line 3-3 of Fig. 2 and shows the arrangement of locking mechanism; 65

Fig. 4 is a section taken on the line 4-4 of Fig. 3, showing the mounting for said drum and the locking mechanism therefor; and 70

Fig. 5 is a fragmentary section taken on the same line as Fig. 3, except that the locking mechanism has been disengaged by the key provided.

75 My improved mechanism is especially adapted for apparatus which must be tightly locked in one position and said control being arranged so as to be actuated and released only by an authorized person having a correct key. In Fig. 1, I have shown this 80 control apparatus as applied to a closure for a railway toilet, such application being the subject matter of the copending application before mentioned.

85 The receptacle *a* to be actuated is hingedly carried upon the floor *b* of a railway coach and is provided with sheaves *c* at each side which ride upon pivot arms *d* carried by one of the side members *b'* of said car. A cable *e* is connected to said arm as at *d'* 90 and the other end is wound about the control drum *f* with which my invention is concerned. Thus by rotating said drum to wind the cable upon its periphery, the receptacle will be moved up to the position 95 shown in Fig. 1, and when said drum is released said receptacle *a* is permitted to fall into opened position.

100 My improved drum *f*, and control mechanism therefor, is adapted to be mounted so as to extend through a vertical wall *b* of the toilet room so that the cable *e* does not have to pass through any portion of said wall and is thus concealed within said room. Said drum *f* is mounted within said toilet room 105 and is provided with a portion *f'* of smaller diameter which is journaled in the bearing member *g* which is provided with a circular flange *g'* which forms substantially a bushing for said portion *f'*. The entire mechanism is mounted within a casing *h* made in two halves and adapted to be fastened to

gether by a number of bolts i , as shown in Fig. 4. Said bolts i not only hold the halves of said casing h together but also hold the bearing member in place. Mounted upon a further reduced portion f^2 of said drum is a ratchet k which is held against rotation relatively thereon by a key j . Said drum portion f is further reduced in diameter and terminates in a squared end f^3 which extends centrally into the aperture l in the face of said casing. Said squared end f^3 is thus in position to permit a key having a squared aperture to be fitted thereover and to turn the same, thus turning the ratchet therewith. Pivottally attached to said bearing member is a pawl m pivoted at m' and adapted to engage said ratchet and a spring n carried thereby bears against a pin o and holds said pawl in engagement with the teeth of said ratchet and thus permit said ratchet to turn in but one direction.

An outstanding cylindrical portion g^3 is provided on the bearing member g adjacent the free end m^2 of the pawl m and supports a pin p which is rotatably mounted within the portion p^3 as at g^2 . A transverse slot m^3 is provided in the portion g^3 so that the free end m^2 of the pawl m will enter and engage a notch p^4 , in the pin p . A set screw q which is provided in the portion g^3 and bears in an angular groove p' in the pin p , thus holding the said pin in place. The pin p terminates in a squared end p^5 which extends into the aperture r in the face of said casing. It is arranged centrally therein similar to the squared end f^3 for said drum. Said squared end p^5 is preferably identical to the squared end f^3 so that the same keys may operate the same. The end of the cable e is fastened to the drum f by being passed through a hole f^4 in the periphery of said drum and the cable being knotted as e' within said drum so as to prevent it from being pulled through said aperture f^4 . Thus when said drum is turned by a key s said cable is wound upon the periphery of said drum, said drum being rotated until the receptacle a or other device, connected to said cable is moved into closed position. In this position the pawl m engages the teeth of the ratchet k and holds said drum and thus the receptacle a tightly in position so that there is no play. To release said pawl the key s is transferred from off of the squared end f^3 and is arranged to engage the squared end p^5 . Said cam-shaped pin p upon which the free end of the pawl rests is provided with a notched portion p^4 which is normally arranged to receive said end m^2 of the pawl. Said cam-shaped pin is prevented from being turned in one direction because the face of said notch engages the end m^2 of said pawl and thus is prevented from turning in a clockwise direction, as shown in Fig. 5, and thus the portions are arranged

so that the devices cannot be inadvertently operated in the wrong direction. When the key s is turned so as to rotate the control pin p in a counter-clockwise direction, however, the point p^5 on said pin bears against said free end m^2 of said pawl and lifts the same so that it is disengaged from said ratchet and is forced upwardly against the action of the spring n until said pawl m and said spring n are forced tightly against the pin o . As soon as said ratchet is released the weight of said receptacle causes the same to fall into disengaged position. Said pin o is positioned relatively to the pawl m so that the point p^5 is prevented from passing from off the end of said pawl, as is shown in Fig. 5. That is, the pawl, when arranged in utmost released position, assumes an oblique angle with the end of said pawl and is prevented from passing over the end thereof because the distance between the axis of said pin p and the end of said pawl m is relatively less than the distance said point p^5 is spaced from said axis.

It is to be observed that said pawl releasing mechanism will operate even though the drum has wound said cable up very tightly so as to eliminate any play whatsoever. That is, the engaging face of said pawl and the corresponding face of the ratchet teeth are arranged so as to be substantially parallel and to extend in a plane substantially tangential to the pivot m' for said pawl, and thus although the pawl engages said ratchet teeth very firmly, said pawl is permitted to be raised to disengaging position because of said relative arrangement.

I claim:

1. In control mechanism of the character described, a drum having an axially arranged stem, a ratchet mounted on said stem, a pivoted pawl adapted normally to engage said ratchet, a rotatable cam-element adapted to engage the free end of said pawl and lift the same out of engagement with said ratchet, said drum and said rotatable cam-element each provided with a key-engaging portion, said key engaging portions being uniformly proportioned.

2. A control mechanism comprising a rotatable drum having an axially arranged stem portion, a casing composed of two separable halves adapted to house said control mechanism, and fastening means adapted to hold said halves together.

3. A control mechanism comprising a rotatable drum having an axially arranged stem portion, a casing composed of two separable halves adapted to house said control mechanism, a central web extending transversely of said casing, and fastening means adapted to hold said halves and said web together.

4. A control mechanism comprising a rotatable drum having an axially arranged

stem portion, a casing composed of two separable halves adapted to house said control mechanism, a central web extending transversely of said casing, fastening means adapted to hold said halves and said web together, said transverse central web forming a journal for the stem of said drum.

5. A control mechanism comprising a rotatable drum having an axially arranged stem portion, a casing composed of two separable halves adapted to house said control mechanism, a ratchet fixed to said stem, the end of said stem exterior of said ratchet being formed to receive a key and coinciding with an aperture in the adjacent half of said housing.

6. A control mechanism adapted to extend through and be supported by a vertical partition, comprising a rotatable drum having an axially arranged stem portion and adapted to extend through and be journaled in said vertical partition, a ratchet fixed to said stem, a pivoted pawl arranged to engage said ratchet to prevent it from turning in one direction, and a cam element engaging said pawl and adapted to lift said pawl out of engagement with said ratchet.

7. A control mechanism adapted to extend through and be supported by a vertical partition, comprising a rotatable drum having an axially arranged stem portion and adapted to extend through and be journaled in said vertical partition, a casing composed of two separable halves adapted to be fastened to the opposite sides of said partition and to house said control mechanism, a ratchet fixed to said stem, the end of said stem exterior of said ratchet being formed to receive a key and coinciding with an aperture in the adjacent half of said housing, a pivoted pawl arranged to engage said ratchet to prevent it from turning in one direction, and a cam element engaging said pawl and adapted to lift said pawl out of engagement with said ratchet.

8. A control mechanism adapted to extend through and be supported by a vertical partition, comprising a rotatable drum having an axially arranged stem portion and adapted to extend through and be journaled in said vertical partition, a casing composed of two separable halves adapted to be fastened to the opposite sides of said partition and to house said control mechanism, a central web extending transversely of said casing, said transverse central web forming a journal for the stem of said drum.

9. A control mechanism adapted to extend through and be supported by a vertical partition, comprising, a rotatable drum having an axially arranged stem portion and adapted to extend through and be journaled in said vertical partition, a casing composed of two separable halves adapted to be fastened to the opposite sides of said

partition and to house said control mechanism, a central web extending transversely of said casing, said transverse central web forming a journal for the stem of said drum, the end of said stem exterior of said ratchet being formed to receive a key and coinciding with an aperture in the adjacent half of said housing, a pivoted pawl carried by said web arranged to engage said ratchet to prevent it from turning in one direction, and a cam element also caused by said web engaging said pawl and adapted to lift said pawl out of engagement with said ratchet.

10. A control mechanism comprising, a rotatable drum having an axially arranged stem portion and adapted to extend through and be journaled in said vertical partition, a casing composed of two separable halves adapted to be fastened to the opposite sides of said partition and to house said control mechanism, a central web extending transversely of said casing, said transverse central web forming a journal for the stem of said drum, the end of said stem exterior of said ratchet being formed to receive a key and coinciding with an aperture in the adjacent half of said housing, a pivoted pawl carried by said web arranged to engage said ratchet to prevent it from turning in one direction, a cam element also caused by said web engaging said pawl and adapted to lift said pawl out of engagement with said ratchet, and a stop adapted to limit the degree of movement given to said pawl by said cam.

11. A control mechanism adapted to extend through and be supported by a vertical partition, comprising a rotatable drum having an axially arranged stem portion and adapted to extend through and be journaled in said vertical partition, a casing composed of two separable halves adapted to be fastened to the opposite sides of said partition and to house said control mechanism, a central web extending transversely of said casing, fastening means adapted to hold said halves and said web together and to said vertical partition, said transverse central web forming a journal for the stem of said drum, a ratchet fixed to said stem, the end of said stem exterior of said ratchet being formed to receive a key and coinciding with an aperture in the adjacent half of said housing, a pivoted pawl arranged to engage said ratchet to prevent it from turning in one direction, a cam element also caused by said web engaging said pawl and adapted to lift said pawl out of engagement with said ratchet, and a stop adapted to limit the degree of movement given to said pawl by said cam.

12. In combination with a supporting element, a drum journaled in such supporting element, said drum provided with a pro-

jecting stem at one side, a ratchet mounted on such stem and an arcuate spring-controlled pawl located to engage with said ratchet, the free end of said pawl extending beyond said ratchet, a rotatable cam located and adapted in one position to permit said pawl to be positioned so as to engage with said ratchet and said cam in other position lifting said pawl so as to disengage the latter from said ratchet.

13. In combination with a supporting element, a drum journaled in such supporting element, said drum provided with a projecting stem at one side, a ratchet mounted on such stem and an arcuate spring-con-

trolled pawl located to engage with said ratchet, the free end of said pawl extending beyond said ratchet, a rotatable cam located and adapted in one position to permit said pawl to be positioned so as to engage with said ratchet and said cam in other position lifting said pawl so as to disengage the latter from said ratchet, said ratchet and said cam being respectively provided with key-engaging means, the latter being of uniform proportions in structures so that a single key may be used for operating either one thereof.

ABRAHAM L. LEVY.
